UNITED STATES PATENT OFFICE.

LEONARD R. STEEL, OF CLEVELAND, OHIO.

BOTTLE-RECEPTACLE.

1,108,017.

Specification of Letters Patent.

Patented Aug. 18, 1914.

Application filed March 4, 1911, Serial No. 612,210. Renewed August 12, 1913. Serial No. 784,437.

To all whom it may concern:

Be it known that I, LEONARD R. STEEL, a citizen of the United States, residing at Cleveland, in the county of Cuyahoga and 5 State of Ohio, have invented new and useful Improvements in Bottle-Receptacles, of which the following is a specification.

One object of the invention is to construct the crate member and the refrigerant container so that either or both may be readily removed from the receptacle so as to permit of their being kept in a clean sanitary condition.

In the drawings, forming a portion of this 15 specification and in which like numerals of reference indicate similar parts in the several views:—Figure 1 is a vertical longitudinal section through the receptacle. Fig. 2 is a horizontal section taken on the line 20 2—2 of Fig. 1. Fig. 3 is a transverse section taken on line 3—3 of Fig. 1. Fig. 4 is a side view of one of the longitudinal members of the cell or crate. Fig. 5 is an edge view of the same. Fig. 6 is a view similar to Fig. 4 25 showing one of the transverse members of the cell or crate. Fig. 7 is an edge view of the same.

The invention includes a casing 1 which is constructed preferably of outer and inner 30 end walls 2 and 3, outer and inner bottom walls 4 and 5, outer and inner side walls 6 and 7, and a joint or connecting top member 8. The inner end walls 3 are formed on their vertical edges with vertical recesses 35 9 in which the vertical flanges 10 of the inner side walls 7 are fitted and secured, at 11, by rivets or the like. The inner bottom wall 5 is of rectangular configuration, as herein shown, and it is stamped to form a 40 vertical rectangular flange 12 which embraces the lower portions of the end walls 3 and the side walls 7, being secured there- 45 to by rivets 13. The outer end walls 2 are formed with vertical end recesses 14 in which the flanges 15 of the outer side walls 6 are mounted and secured, at 16, by rivets. The outer bottom wall 4 is provided with a 50 vertical rectangular flange 17 which is secured, at 18, by rivets to the outer end walls 2 and the outer side walls 6. The joint or connecting member 8 is of rectangular configuration and in transverse section it is of a stepped construction, being formed with the horizontal shoulders 19 and 20 which are 55 connected with each other by a downwardly

and inwardly inclined connecting shoulder 21. The shoulder 20 is provided with a depending rectangular flange 22 which is secured, at 23, by rivets to the inner end walls 3 and the inner side walls 7. A similar flange 24 is soldered or otherwise suitably secured to the outer end walls 2 and the outer side walls 6. A sheet metal collar 25, preferably of rectangular configuration, is interposed between the inner and outer bottom walls 4 and 5 so as to brace them and to hold them against swelling under expansion. The inner and outer walls of the casing described are separated from each other so as to form an intervening space in which the 60 non-heat conducting insulating material 26 is placed. This material may be cork, asbestos, mineral wool, or straw-board or the like, and when placed between the walls, as shown, it serves to hold the contents of the jacket at the same temperature and protects against the transfer of heat through the 65 walls.

The casing is provided with a cover 27 which preferably includes spaced inner and outer walls 28 and 29, being separated from each other by the insulating material 30. The bottom wall is formed with a rectangular stepped portion 31 including surfaces 32, 33 and 34 to contact with the similar surfaces on the stepped member 8 hereinbefore described. The cover is hinged to one of the vertical sides of the casing, as at 35. At the opposite side, the casing is provided with a staple 36 which is designed to receive the hinged hasp 37 on the cover. When the hasp and staple are engaged with each other they may be secured together or locked with each other by any suitable well known form of locking device, (not 90 shown).

A refrigerant container is removably mounted in the casing and it includes a bottom 38 and the side and end walls 39 and 40. The side and end walls are secured, at 41, to the bottom 38 and at their upper ends the side and end walls are provided with inwardly presented horizontally disposed supporting flanges 42 which are designed to support a perforated bottle rest 43. This 100 support is of a configuration and size so as to form a cover for the refrigerant container, being spaced from the bottom 38, as shown. A column 44 extends upwardly from the bottom 38 and is designed to assist in sup- 105 116

porting the bottle support 43 to hold the same against sagging under the weight of bottles thereon.

A crate 45 is removably fitted in the casing 1 and is adapted to be supported therein upon the bottle support. This member includes longitudinal plates 46 and transverse plates 47. The plates 46 are provided with downwardly extending vertically disposed 10 slots 48. The transverse plates are formed to provide upwardly extending vertical slots 49. These slots are designed so as to permit of an interchangeable association of the longitudinal and transverse members with each 15 other. The slots 48 and 49 are preferably constructed by forming substantially L-slots in the plates and the slit portions are bent outwardly to form brace flanges or webs 50. These braces contact with the adjacent 20 plates so as to give to the crate considerable strength and rigidity. When the longitudinal and transverse plates are assembled, as shown in Fig. 3 of the drawings, the crate presents a plurality of vertical cells 51, each 25 of which is designed for the reception of a bottle of liquid, and as shown, each cell is in direct communication with one of the perforations 52 in the bottle support 43 hereinbefore described. The cells are also in communication with each other through the provision of openings 53 in the longitudinal plates or members and similar openings 54 in the transverse plates or members. The top of the crate is spaced from the closure 30 35 of the casing so that the refrigerant or heat products will be permitted to circulate freely around the top portions of the receptacles or bottles in the cells.

The device herein constructed is extremely 40 simple, the various elements of the structure are separable and may be readily disconnected from each other so that each part can be thoroughly cleaned and kept in a perfect sanitary condition. The device, as illustrated and described, is provided with a 45 plurality of cells which are adapted to re-

ceive a great number of bottles or vessels in which their liquids are to be kept as near as possible at the same temperature and the device may be used to a decided advantage 50 as a shipping casing for the shipment of milk or the like or beverages such as beer, wines or the like, and may be found also most useful for household or restaurant purposes. 55

The outer end walls 2 of the casing are provided with attaching plates 54 on which are mounted suitable handles 56. All corners of the casing are protected by corner straps or brackets 57. 60

I claim:—

A casing, a refrigerant container mounted in the bottom thereof, a foraminous member extending across and supported by said container and removable therefrom and closing 65 the top thereof, a crate comprising interfitting partitions arranged relatively to define separate cells above the plane of the refrigerant container and supported by said foraminous member and having its companion 70 partitions slotted vertically, the slots of one partition receiving portions of an adjacent partition, and bracing portions stamped from all of the slots and extending vertically of the partition, the braces of one partition being disposed at the sides of adjacent partitions, the said partitions having 75 passages therein whereby lateral communication is established between the respective cells, the foraminous support establishing 80 vertical communication between the refrigerant container and the cells, the top of the crate being disposed in spaced relation to the top of the casing whereby to form an intervening cold air circulating space therebetween. 85

In testimony whereof I affix my signature in presence of two witnesses.
